UNITED STATES PATENT OFFICE.

WILLIAM I. DONALDSON, OF PAULSBORO, NEW JERSEY, ASSIGNOR TO THE E. I. DU PONT DE NEMOURS POWDER COMPANY, OF WILMINGTON, DELAWARE, A CORPORATION OF NEW JERSEY.

CARTRIDGE-LOADING MACHINE.

No. 899,592.

Specification of Letters Patent.

Patented Sept. 29, 1908.

Application filed December 1, 1906. Serial No. 345,908.

To all whom it may concern:

Be it known that I, WILLIAM I. DONALDSON, a citizen of the United States, residing at Paulsboro, county of Gloucester, and 5 State of New Jersey, have invented a new and useful Improvement in Cartridge-Loading Machines, of which the following is a full, clear, and exact description, reference being had to the accompanying drawings, which 10 form a part of this specification.

The object of the invention is to provide a power-machine for loading paper shells with dynamite.

The machine embodying the invention 15 embodies many of the features shown in the patent of Hiram P. Hall, No. 601,138, issued March 22, 1898, but also embodies many novel features designed to render the machine safer, more rapid, more convenient and 20 almost wholly automatic.

In the drawings: Figures 1 and 2 represent on two sheets a front elevation of the machine, partly in section, the folding mechanism being omitted from Fig. 2; Fig. 1 showing the upper half of the machine which is supported upon an upper floor of the building, and Fig. 2 showing the lower half of the machine, which is on the floor below and is connected through the ceiling with the part 25 on the floor above. Fig. 3 is a vertical section through the devices for immediately actuating, locking and leveling the plungers. Fig. 4 is a side elevation of the upper part of the machine. Fig. 5 is a section on the line 30 5—5 of Fig. 1. Fig. 6 is a section on the line 6—6 of Fig. 1. Fig. 7 is a vertical section through the lower half of the machine on the line 7—7 of Fig. 2. Fig. 8 is a side elevation 35 of a part of the lower half of the machine, looking toward the right side of Fig. 2. Fig. 40 9 is a side elevation of a part of the lower half of the machine, looking toward the left hand side of Fig. 2.

The second story part of my machine comprises (see Fig. 1) a framework 10 in the lower portion of which is journaled a horizontal shaft 11 driven by a pulley 110. On the shaft 11 are eccentrics 111 (see also Fig. 4) engaging straps 112 connected to the 45 cross-head 12 by means of rods 113. The cross-head 12 slides vertically on guides in the framework 10. The described driving connections to the cross-head 12 impart to it an up-and-down reciprocation.

50 The office of the cross-head is to recipro-

cate the series of vertical loading plungers 13, which have a peculiar connection with the cross-head, as will be hereinafter explained. These plungers are each made in two or more sections and extend from the top of the machine in the upper story down through the floor to the story below, and operating devices for these plungers are located in the upper story away from the lower floor where the loading of the dynamite is effected. The 60 lower ends of the plungers are connected to tamps 130 made of wood, rubber or other non-metallic material. In the drawings (Fig. 2) a single tamp is secured to and operated by two plungers; but this merely illustrates 65 one of several modes of connecting the tamps, as it is obvious, for instance, that one tamp may be secured to each plunger where the cartridges to be packed are smaller and twice as numerous. The connections between the 70 plungers and tamps consists of small tubular sections 131 secured to the plungers and into which the upper ends of the tamps are inserted. The lower ends of the tamps play 75 through nipples 140 in the removable bottom of the dynamite receptacle 14 and penetrate the paper shells to be loaded, which shells are held in a revolving or shell-holding drum 15 rotating about a horizontal axis.

The revolving drum 15 (see also Fig. 7) 80 consists of the end heads 150 secured to the shaft 16, the hub 151 secured between the end heads and the shuttles 17—18, that directly hold the shells and that will be hereinafter more fully described. The shaft 16 is journaled in bars 160 and 161 at opposite sides of the machine. These bars are vertically, 85 slideable in guides on the frame-work 100. This construction permits the drum 15 both to revolve and to be raised and lowered bodily. 90 The revolution about its axis is to permit each shuttle containing a series of shells to be successively brought beneath the loading tamps; the upward movement of the drum is to permit it to be raised when brought under 95 the tamps so as to cause the empty shells in the shuttle to be telescoped or slipped over the discharge nipples 140 in the bottom of the hopper 14; and the downward movement of the drum is to disengage the loaded 100 shells from the discharge nipples and permit the drum to be rotated. The means for rotating, and imparting the stated up-and-down movement to the drum will be herein- 105 after described.

Each shuttle, of which there are six, arranged radially of the drum axis, is composed of a pair of bars 17 and 18 arranged between the heads of the drum parallel to its axis. One of the bars 17 is fixed and the other, 18, is hinged at its inner end, and they contain shell seats having a series of channels of semi-cylindrical shape arranged exactly opposite to each other, so that when the two bars are brought together, cylindrical shell-receiving cavities are formed. The bar 18 is provided with a disk 180, which forms the bottom of the shell-holding cavity when the two bars are brought together. On the outside of the hinged bar 18, near each end thereof, is an abutment 181, against which is adapted to bear a cam 19 on a stud turning in bearings in the drum-heads 150, and operated by a lever 190.

When a shuttle reaches the point opposite the head of the arrow, Fig. 7, it is filled with shells by the operator, who deposits the shells in the shell cavities carried by the hinged bar 18. The operator then turns the lever 190 outwardly, causing the cams 19 to bear against the abutment 181 in such manner as to move the hinged bar toward the fixed bar, closing the shell cavities. After the drum is given a sixth turn this shuttle is filled. After it is given another sixth turn the ends of the shells are turned down by means hereinafter described. In the subsequent movement of the drum, the levers 190 engage fixed cams 20 secured to the frame work, which retracts the cams 19 and unlocks the bar 18. At the next turning movement of the drum, lugs 182 on the hinged bar 18 engage other fixed cams 200, which positively retract the hinged bar 18 and allow the contained shells to fall into the discharge trough 21.

It has been stated that the drum is raised before each loading operation and dropped after each loading operation, then turned a one-sixth turn and then again raised preparatory to the next loading operation, and so on. After one series of shells is filled, the projecting outer edges of the shells are crimped and folded after the next upward movement of the drum by the following means (see Figs. 7 and 8).

22, 23 are folding bars extending outside the drum and parallel to its axis and movable radially of the drum axis in guides 61 on the frame. The folding bar 22 carries a series of 55 annular cup-shaped folders, adapted, when the bar 22 is moved radially inwardly, to engage the outer edges of the projecting outer ends of the shells and bend them inwardly. The folding bar 23 supports a series of plun- 60 gers 232 fitting within the annular folders and adapted, when the folding bars 23 are moved inwardly, to strike the edges of the shell inturned by the folding bar 22 and complete the fold and permanently close the 65 shell upon its contents.

The folding bars are actuated by the plunger 233 working in the cylinder 24, and secured to the cross-bar 23. Air under pressure is admitted to the cylinder 24 through the pipe 240. Secured to the folding bar 22 are 70 brackets 220 supporting cylinders 221, within which work plungers 231 attached to brackets 230 on the cross-bar 23. The cylinders 221 are connected by the flexible pipe 222 with the pressure supply pipe 620. 75 As the plunger 233 moves radially inward, the folding bars 22 and 23 first move in together, and the folding bars 22 perform their initial folding operation. After the folding bars 22 contact with the shuttle, the folding 80 bar 23 continues to move against the pressure in the cylinders 221, causing the plungers 232 to complete the fold as described.

To stir or agitate the dynamite within the receptacle 14 so as to maintain a uniform distribution of the dynamite within the hopper and maintain it in proper condition to feed freely, there are provided two shafts 25 respectively, in front of and behind the series of tamps 130 (see Figs. 2 and 7). Secured 85 to each shaft are two series of radial fingers 250 on opposite sides of the shaft, the fingers of one series being staggered with respect to the fingers of the other series. The fingers are of such length that they will just clear the 90 front and rear faces of tamps and are so disposed on each shaft that the projections 251 on the ends of the fingers just clear the side faces of the tamps. By this arrangement, not only is the dynamite thoroughly agitated, 95 but the dynamite is prevented from sticking to the tamps. These shafts are removably secured at the ends to boxes 253, 254, mounted respectively on shafts 257, 258 journaled in the frame. One of the two shafts 258 has at 100 one end a sprocket wheel 252, which, through the medium of a sprocket chain 259 is driven from a sprocket wheel 50 (see Fig. 1) on the main driving shaft 11. The shaft 25 thus driven, drives the other shaft 25 by means of 105 the gear wheels 255, 256 (see Figs. 2 and 8).

The means for actuating the plungers and tamps will now be described. As hereinbefore stated this is effected by the cross-head 12. This cross-head (see Figs. 1, 3 and 6) 110 has a series of square channels for the reception of the plungers 13. Each channel has on one side a gib 120 held in engagement with its corresponding plunger by means of a spring 121 whose tension is so regulated by 115 set screws 122 as to give any desired degree of frictional contact. This frictional connection of the plungers with the cross-head causes the latter to reciprocate the plungers, but still leaves them independent thereof so 120 they may slide through the cross-head.

At each downward stroke of the cross-head, the dynamite packed at that stroke causes the plungers to rise somewhat with respect to the cross-head, the plungers rising 130

as soon as the resistance of the dynamite to further compression exceeds the force holding the plungers and cross-head in frictional contact. The plungers each thus gradually rises with respect to the cross-head during the loading operation until its shell is filled and packed to the desired extent, at which time it is necessary to lock the plunger from again moving down. This is effected by means of the cross-head 26 (see Fig. 5) carrying dogger-pins 260 pressed outwardly by springs 261, each dogger pin springing into engagement with an orifice 135 in the corresponding plunger 13 as soon as the latter is raised, at the end of an upward stroke of the cross-head, to a height sufficient to cause the pins 260 and orifices 135 to register. The plunger is raised to this height as soon as it has filled and packed its corresponding shell to a predetermined extent. After any one or more plungers are locked to the cross-head 26, the cross-head 12 reciprocates, without operating these plungers, until all the remaining plungers are raised to a similar height and similarly locked to the cross-head 26. After all the shells have been loaded and all the plungers locked to the cross-head 26, the latter is moved laterally to withdraw the dogger pins 260 from the orifices in the plungers. This occurs at the end of the up-stroke of the cross-head 12 and is effected automatically as will be hereinafter described, after the drum has brought a new series of empty shells in line with the tamps. When the plungers, after being so unlocked from the cross-head 26, are carried down by the cross-head 12, it will be understood that the tamps are projected into the shells only the distance to which they are projected at the end of the previous loading operation; whereas, to enable the tamps to act effectively, they should move nearly to the bottoms of the shells so as to properly pack the first charge of dynamite and then, as before described, be subsequently gradually forced up with relation to the cross-head 12 as more and more dynamite is packed in the shells. To effect this result the plungers, at the first up-stroke of the cross-head 12 following the unlocking of the plungers, are caused to be moved down with relation to the cross-head 12 the distance necessary to cause the plungers to be forced into the shells the desired distance at the succeeding down-stroke of the cross-head 12. This is effected by moving into the path of the plungers a cross-head 27 against which the ends of the plungers impinge at the said up-stroke of the cross-head 12. After the cross-head 27 thus depresses all the plungers to a common level it is withdrawn from operative position and the locking cross-head 26 is moved into operative position so as to be ready to act upon the plungers, as before described, after they have loaded the shells as before described.

It will therefore be understood that the locking cross-head 26 is normally in operative position while the leveling cross-head 27 is normally in inoperative position. The cross-heads are moved out of their normal positions at the proper times by automatic mechanism that will now be described.

The ends of the cross-heads 26 slide laterally in guides 28 on the frame 10 and the cross-head normally held in its operative position by pins 280 engaging orifices in the ends of the cross-head. Springs 281, interposed between the guide frame and cross-head, are effective to move the cross-head into its inoperative position when the pins 280 are withdrawn.

The ends of the cross-head 27 slide laterally in guides 29 on the frame 10 and said cross-head is normally held in its inoperative position by pins 290 engaging orifices in the ends of said cross-head. Springs 291, interposed between the guide-frame and cross-head, are effective to move the cross-head into its operative position when the pins 290 are withdrawn.

Each pin 280 is connected, by means of a link 282, with one end of a lever 30 pivoted, between its ends, to the frame 10. Each pin 290 is connected, by means of a link 292, with the other end of the corresponding lever 30.

31 is a shaft, extending between the opposite sides of the frame and having arms 310 extending under the ends of levers 30 adjoining the links 282. By imparting a partial turn to the shaft 31, the levers 30 are rocked on their pivots, withdrawing the pins 280 from the cross-head 26, and the pins 290 from the cross-head 27. The shaft 31 is turned, at the end of the stated up-stroke of the cross-head, by the following means (see Fig. 4).

32 is an arm on the shaft 31.

33 is an upright tripping bar on the cross-head 12.

320 is a lug or abutment adapted to slide on the arm 32. A spring 321, connecting the shaft 31 and lug 320 normally holds the lug toward the inner end of the arm. At each up-stroke of the cross-head 12, the upper end of bar 33 moves under the outer end of arm 32 but does not move up far enough to operate it. When, however, the lug 320 is moved toward the outer end of arm 32 and in line of movement of the bar 33, the latter strikes the lug and operates the arm 32, turning the shaft 31. The lug 320 is moved outwardly on the arm 32 by means of a bell-crank lever 34 pivoted on the frame and actuated by a cylinder 35 connected with the pressure supply-pipe 350, the piston rod 340 of the cylinder 35 being connected with the bell-crank. The pipe 350 is connected through pipe 750, with the pipe 510 hereinafter referred to.

115

120

125

130

It will now be understood that when it is desired, at the beginning of a loading operation, to unlock the plungers 13 from the cross-head 26 and depress the plungers to a common level by means of the cross-head 27, air pressure is admitted to the cylinder 35, which, through the bell-crank 34, moves the lug 320 into position to enable the arm 33 on the cross-head 12 to strike the lug and turn the shaft 31, thus causing the arms 310 to rock the levers 30 and withdraw the pins 280 and 290 from their respective cross-heads.

Immediately upon the withdrawal of the pins 280 from the cross-head 26, the latter is moved, by its actuating springs 281, laterally to disengage its dogger-pins from the plungers and the latter move down with the cross-head. As soon as the upper ends of the plungers clear the cross-head 27, the latter moves out, under the influence of its actuating springs 291, into the path of the plungers, so that, during the next upward stroke of the cross-head 12, the plungers strike the cross-head 27 and are thus depressed to a common level as before described.

At the completion of the last stated upward stroke of the cross-head, the cross-head 26 is returned to its normal operative position and the cross-head 27 returned to its normal inoperative position by the following means. 36 is a bell-crank pivoted to the frame. One of its arms engages the side of the cross-head 26 opposite the spring 281. 37 is a second bell-crank pivoted to the frame and one arm of which engages the side of the cross-head 27 opposite the spring 291. 40 is a bracket on the cross-head 12. 38, 39 are upright arms on the bracket 40. When the cross-heads 26 and 27 are in their normal positions, springs 360 and 370, connecting respectively cross-head 26 and bell-crank 37, hold the outer arms of the bell-cranks up so that they just fail to be engaged by the arms 38 and 39. But after the cross-heads 26 and 27 are moved away from their normal positions, the outer ends of the bell-cranks 36 and 37 are moved down so that, at the next up-stroke of the cross-head, the arms 38 and 39 engage the bell-cranks 36 and 37 respectively and return the cross-heads to their normal positions. As soon as the cross-heads are returned to their normal positions, the springs 41, interposed between a bracket on the frame and the lever 30, return the latter to its normal position and force the pins 280 and 290 into engagement with their respective cross-heads. In the meantime, the supply of air to the cylinder 35 has been cut off and the lug 320 has been withdrawn by spring 321 from above the bar 33, so that, in the last stated up-stroke of the plunger, the bar 33 fails to turn the shaft 31 and the springs 41 are thus free to operate as soon as the orifices in the cross-heads 26 and 27 are brought opposite the pins 280 and 290.

The dynamite is conveyed to a hopper 42 (see Fig. 7) communicating with the receptacle 14 by means of a traveling apron 43 engaging the drum 440 on the shaft 44. On the shaft 44 is a pulley 441 which, by means of a belt 45, is driven from a pulley 46 (see Fig. 1) on the main driving shaft 11. The pulley 46 is loose on its shaft but is clutched thereto by means of a friction clutch, one member 470 of which is connected, by arms 471, with a collar 47 feathered on the shaft, while the other member 460 is secured to the pulley 46. Pivoted to the floor of the second story is a lever 48. Between its ends this lever is connected with the collar 47 and at its upper end the lever is attached to the piston-rod 480 of a cylinder 49, communicating with a pipe 490. The pipe 490 is connected with the supply pipe 620 and is controlled by the hand-valve 491. When compressed air is admitted to the pipe 490, the lever 48 is operated to cause the clutch member 470 to engage the clutch-member 460, thus causing the pulley 46 to turn with the shaft and transmit a movement of rotation to the shaft 44. This actuates the apron 43 and causes dynamite to be conveyed therefrom into the hopper 42.

The following means are provided to elevate the bars 160 and 161 carrying the journals for the shaft 16 of the drum 15 (see Figs. 2 and 7). 51, 51, are cylinders on opposite sides of the frame. 510 is an air-supply pipe communicating with the cylinders. 52, 52, are pistons in said cylinders secured to the lower ends of bars 160 and 161 respectively. To compel the two ends of the drum shaft to move in unison, an equalizing device is provided consisting of a cross-shaft 53 turning in bearings in standards on the lower cross-beams 101 of the frame, gears 530, 530 on the ends of shaft 53, and racks 162, 162, on the bars 160 and 161 respectively, engaging the two gears respectively.

511 is a three-way valve in the pipe 510 which may be turned to connect the pipe 510 with either the supply valve 620 or the exhaust 512, thus enabling the lifting and dropping of the drum to be controlled by hand.

To turn the drum shaft, air under pressure, admitted to the cylinder 54 from the supply pipe 540 (see Fig. 8), forces up the plunger 55. The plunger 55 is connected by means of a link 561, with a lever 560 pivoted on a pin in line with the end of the drum-shaft 16 and carrying a pawl 56 engaging a ratchet wheel 57 on the drum-shaft. As the plunger 55 rises, the pawl 56 engages the ratchet 57 and turns the drum-shaft a sixth turn. The supply of air to the cylinder 54 is cut off by means of a valve 541 on the pipe 540 which valve is so operated as the drum rises by means of pins 163 on the bar 161 operating an arm 542 secured to the valve 541. When the drum is lowered, the valve 541 is operated

- to again open the cylinder 54 to the pressure supply, thus causing the drum to be given another turn. A spring 551 normally holds the plunger 55 down.
- 5 Pivoted to the bar 161 is a tripping lever 58 which is held against a pin 580 on a block 581 by means of a spring 582, the block 581 being secured between the upright posts of the frame 100 and directly above the bar 161.
- 10 59 is a bell-crank lever pivoted on the frame 100, the short horizontal arm of the bell-crank being in line of travel of the lever 58 in the upward movement of the bar 161 and the depending lower arm of the bell-crank resting against the pin 590 on the frame 100 and being connected, by a link 601 with an arm 600 secured to the three way valve 60. The valve 60 is located at 15 the junction of pipe 240 (which, as previously described, supplies air to the cylinders 24 for actuating the folding bars 22 and 23), the supply pipe 620, and the open exhaust 630. The pipe 620 is also connected, by pipes 640, 20 with the cylinders 64 whose plungers 641 are attached to projections 642 on the folding bar 23.
- 25 76 is a cylinder communicating, by pipe 760, with the pipe 240, and having a plunger 602 attached to the arm 600. As the bar 161 rises, the lever 58 thereon actuates the bell-crank 59, which, through the link 601, moves the valve arm 600 to operate the valve 60 and open communication from the 30 supply pipe 620 to pipe 240 and close the exhaust 630. Air is thus admitted to the cylinder 24, and the folding bars 23 and 22 are operated, as hereinbefore described, against the constant pressure in cylinders 64 and 35 221, the areas of whose piston heads are less than the areas of the heads of plungers 233. As the folding bars complete their inward movement, a lever 65, pivoted on the folding bar 23 and extending through a guiding 40 eye 650 on the frame, strikes the lower end of the lever 58 and withdraws the upper end of lever 58 from under the horizontal arm of the bell-crank 59. The plunger 602 in cylinder 76 then returns the lever 600 and valve 45 60, as well as link 601 and bell-crank 59, to their normal positions; thus closing communication between pipe 620 and pipe 240 and opening communication between pipe 240 and exhaust pipe 630. The constant 50 pressure in cylinders 64 thereupon becomes effective to operate the plungers 641 to return the folding bars 23 and 22 to their inoperative positions.
- 55 The mechanism for turning the drum and the mechanism for controlling the operation of the valve 60 are contained within a box 60 (see Figs. 1 and 8) secured to the frame 100.
- 60 To prevent the drum 15 from moving more than a sixth turn, there is provided (see Fig. 65 9) a dog 66 carrying a pin 660 engaging a slot 670 on a plate 67 secured to the frame 100, the dog moving vertically in guides in said plate. On the end of the drum shaft is a wheel having a rim 69 and lugs 68 secured 70 sixty degrees apart to said rim. One of the jaws 661 of the dog 66 has a cam face adapted to be struck by a lug 68, which lifts the dog 66 until the lug 68 rides beyond the jaw 661, whereupon the dog 66 drops. The lug 68 is 75 locked from further movement by the longer jaw 662 and is prevented from receding by the jaw 661. Thus the drum shaft is held from rotation and continues to be so held when the drum is lifted as before described, 80 the dog 66 moving upwardly with the drum and its appurtenances.
- 85 Pivoted to the plate 67 is a bell crank tripping lever 70 the outer end of its short horizontal arm being in line with the pin 660 and beveled to permit the pin to strike, turn, and pass it as the dog 66 moves up. The long vertical arm of the bell-crank is in line of travel of the pins 690 projecting laterally from the rim 69. When, after the loading 90 and folding operations, the drum is permitted to drop as above described, the dog 66 is prevented from dropping by the pin 660 engaging the upper face of the short horizontal arm of the bell-crank 70. The drum 95 is thereupon unlocked from the dog 66 and free to be given another one-sixth turn. As the drum turns, a pin 690 on the ring 69 engages the hanging arm of the bell crank 70 and turns the same to withdraw the short 100 horizontal arm of the bell-crank from under the pin 660, whereupon the dog 66 drops and is in position to engage the next lug.
- 105 The described mechanism for stopping the drum for moving beyond a sixth turn and for holding the drum stationary during the folding and loading operations is contained within the box 71 (see Figs. 1 and 9) secured to the frame 100.
- 110 The discharge trough 21 is secured to end bars 72, which are secured to levers 720 pivoted on studs 721 projecting inwardly from the frame 100 (see Figs. 2, 7 and 9). Secured to the end bars 72 are arms 73 connected, by links 730, with a cross-bar 74. 115 Secured to the middle of the cross-bar is a plunger 740 working in a cylinder 75 communicating with a pipe 750, which in turn communicates with the pipe 510. When pressure is admitted to the cylinder 75, the plunger 740, through the connections described, lifts the discharge trough 21 into a position that enables the operator to remove the cartridges without the necessity of stooping.
- 120 125 It will be understood that when the valve 511 is operated to admit pressure to the pipe 510 and cylinders 51 to lift the drum, pressure is simultaneously admitted to the cylinder 35 (which dictates the operation of the 130

mechanism for first unlocking and then leveling the plungers) and also to the cylinder 75 (which causes the trough 21 to rise). Thus the operator can remove the loaded cartridges from the trough during the loading and folding operations. As the drum completes its upward movement it operates the train of mechanism which operates valve 60 to admit pressure to the pipe 240 and cylinder 24, thus causing the folding mechanism to be actuated. After the folding mechanism is actuated, the folding mechanism itself unlocks the chain of mechanism holding the valves 60 in the last-named position and permits the pressure admitted to the cylinder 76 from the pipe 240, to open the pipe 240 and cylinder 24 to the exhaust and return the folding mechanism to inoperative position. When the valve 511 is operated to connect cylinders 51, 35 and 75 to the exhaust, the drum and trough drop and the plunger-locking mechanism is reset. As the drum drops, it actuates the valve 541 to admit pressure to the cylinder 54, thereby causing the drum to be given a sixth turn. Thus the cycle of operations is completed.

Having now fully described my invention, what I claim and desire to protect by Letters Patent is:

30 1. In a machine for loading shells, the combination with a series of independent plungers, of actuating mechanism therefor in yielding engagement therewith whereby the reciprocating plungers are operated in consonance with said actuating mechanism except when they encounter a predetermined resistance, locking mechanism adapted to lock each plunger when it is retracted to a definite extent and hold it out of action, 35 means to disengage said locking mechanism from the plungers thereby unlocking them, leveling mechanism normally out of the path of travel of the plungers, and means to move said leveling mechanism into the path of 40 travel of the plungers, thereby, in the upward movement of the unlocked plungers, depressing them to a common level and into position for the next loading operation.

2. In a machine for loading shells, the combination with a series of independent plungers, of actuating mechanism therefor in yielding engagement therewith whereby the plungers are operated in consonance with said actuating mechanism except when they 55 encounter a predetermined resistance, leveling mechanism, normally out of the path of travel of the plungers, means, arranged to be operating while the plungers are in their forward position, to move said leveling mechanism laterally with respect to the direction of extension of the plungers and into their path of travel, thereby depressing them on their upward movement to a common level and into position for the next loading operation,

and means to thereafter restore the leveling mechanism to its normal position.

3. In a machine for loading shells, the combination with a series of independent plungers, of a cross-head yieldingly engaging the same whereby the plungers are operated in consonance with the cross-head except when said plungers encounter a predetermined resistance, locking mechanism adapted to independently lock each plunger from operation when it is retracted to a definite extent, means to move the locking mechanism into operative position, and a device moving with the actuating cross-head adapted to actuate said means.

4. In a machine for loading shells, the combination with a series of independent plungers, of actuating mechanism therefor including means enabling each plunger to move relatively to said actuating mechanism when encountering a predetermined resistance, a locking device for each plunger to hold it out of action when its shell has been filled, means to withdraw said locking devices and permit said mechanism to again actuate the plunger back and forth, leveling means to stop the back movement of the plungers before the back movement of their actuating mechanism is completed, and means controlled by said actuating mechanism to move the leveling means out of operative position.

5. In a machine for loading shells, the combination with a series of independent plungers, of a cross-head yieldingly engaging the same whereby the plungers are operated in consonance with the cross-head except when said plungers encounter a predetermined resistance, locking mechanism adapted when in operative position to independently lock each plunger from operation when it is retracted to a definite extent, leveling mechanism adapted when in operative position to engage said plungers and move them to a common level, means to move the locking mechanism into operative position and the leveling mechanism into inoperative position, and devices moving with the actuating cross-head adapted to actuate said means.

6. In a machine for loading shells, the combination with a series of independent plungers, of a cross-head yieldingly engaging the same whereby the plungers are operated in consonance with the cross-head except when said plungers encounter a predetermined resistance, a second cross-head, locking devices thereon adapted to engage the plungers when retracted to a definite extent and hold them stationary, means to release the second cross-head from the plungers, and a third cross-head adapted, in the upward movement of the unlocked plungers, to move all the plungers forwardly with respect to the first cross-head.

7. In a machine for loading shells, the combination with a series of independent plungers, of actuating mechanism therefor in yielding engagement therewith whereby the 5 plungers are operated in consonance with said actuating mechanism except when they encounter a predetermined resistance, locking devices, one for each plunger, adapted to operate when the plungers are retracted to a 10 definite extent, a tension device tending to disengage said locking devices from their plungers, means normally holding the locking devices in operative position, leveling mechanism adapted when operative to limit 15 the backward movement of the plungers, a tension device tending to move the leveling mechanism into operative position, means normally holding the leveling mechanism in inoperative position, and mechanism to dis- 20 engage the locking devices and leveling mechanism from their respective holding means.

8. In a machine for loading shells, the combination with a series of independent 25 plungers, of actuating mechanism therefor in yielding engagement therewith whereby the plungers are operated in consonance with said actuating mechanism except when they encounter a predetermined resistance, leveling 30 mechanism adapted to limit the backward movement of the plungers, a tension device tending to move the leveling mechanism into operative position, means normally holding the leveling mechanism in inopera- 35 tive position, and mechanism to disengage the leveling mechanism from its holding means.

9. In a machine for loading shells, the combination with a series of independent 40 plungers, of actuating mechanism therefor in yielding engagement therewith whereby the plungers are operated in consonance with said actuating mechanism except when they encounter a predetermined resistance, locking 45 devices, one for each plunger, adapted to operate when the plungers are retracted to a definite extent, a tension device tending to disengage said locking devices from their plungers, means normally holding the locking 50 devices in operative position, and mechanism to disengage the said locking devices from their respective holding means.

10. In a machine for loading shells, the combination with a series of independent 55 plungers, of reciprocating actuating mechanism therefor yieldingly engaging the same whereby the plungers are operated in consonance with their actuating mechanism except when said plungers encounter a predetermined resistance, of a cross head, locking devices thereon, one for each plunger, adapted to operate when the plungers are retracted to a definite extent, a locking pin normally holding said cross-head in operative position, 60 means to disengage the locking pin from the

cross-head, and a tension device adapted to move said cross-head out of operative position when said locking pin is so disengaged.

11. In a machine for loading shells, the combination with a series of independent 70 plungers, of reciprocating actuating mechanism therefor yieldingly engaging the same whereby the plungers are operated in consonance with their actuating mechanism except when said plungers encounter a predetermined resistance, of a cross-head, locking devices thereon, one for each plunger, adapted to operate when the plungers are retracted to a definite extent, a locking pin normally holding the cross-head in operative position, 75 means operated by said actuating mechanism to disengage the locking pin from the cross-head, and a tension device adapted to move said cross-head out of operative position when said locking pin is so disengaged.

12. In a machine for loading shells, the combination with a series of independent 80 plungers, of reciprocating actuating mechanism therefor yieldingly engaging the same whereby the plungers are operated in consonance with their actuating mechanism except when said plungers encounter a predetermined resistance, of a cross-head, locking devices thereon, one for each plunger, adapted to operate when the plungers are retracted to a definite extent, a locking pin normally holding said cross-head in operative position, 85 means to disengage the locking pin from the cross-head, a tension device adapted to move said cross-head out of operative position when said locking pin is so disengaged, and means operated by said actuating mechanism to return the cross-head into operative position.

13. In a machine for loading shells, the combination with a series of independent 90 plungers, of reciprocating actuating mechanism therefor yieldingly engaging the same whereby the plungers are operated in consonance with their actuating mechanism except when said plungers encounter a predetermined resistance, of a cross-head, locking devices thereon, one for each plunger, adapted to operate when the plungers are retracted to a definite extent, a locking pin normally holding said cross-head in operative position, 95 a tripping bar operated by said actuating mechanism, and connections to the locking pin including an abutment adapted to be moved into the path of the tripping bar to enable the latter to operate said connections to disengage the pin from the cross-head.

14. In a machine for loading shells, the combination with a series of independent 100 plungers, of reciprocating actuating mechanism therefor yieldingly engaging the same whereby the plungers are operated in consonance with their actuating mechanism except when said plungers encounter a predetermined resistance, a cross-head, locking 105 devices thereon, one for each plunger, adapted to operate when the plungers are retracted to a definite extent, a locking pin normally holding said cross-head in operative position, 110 a tripping bar operated by said actuating mechanism, and connections to the locking pin including an abutment adapted to be moved into the path of the tripping bar to enable the latter to operate said connections to disengage the pin from the cross-head.

15. In a machine for loading shells, the combination with a series of independent 115 plungers, of reciprocating actuating mechanism therefor yieldingly engaging the same whereby the plungers are operated in consonance with their actuating mechanism except when said plungers encounter a predetermined resistance, a cross-head, locking 120 devices thereon, one for each plunger, adapted to operate when the plungers are retracted to a definite extent, a locking pin normally holding said cross-head in operative position, 125 a tripping bar operated by said actuating mechanism, and connections to the locking pin including an abutment adapted to be moved into the path of the tripping bar to enable the latter to operate said connections to disengage the pin from the cross-head.

devices thereon, one for each plunger, adapted to operate when the plungers are retracted to a definite extent, a locking pin normally holding said cross-head in operative position, 5 a tripping bar operated by said actuating mechanism, connections to the locking pin including an abutment adapted to be moved into the path of the tripping bar to enable the latter to operate said connections to disengage the pin from the cross-head, a tension device adapted to move said cross-head out of operative position when said locking pin is so disengaged and means operated by said actuating mechanism to return the cross-head to its operative position. 10 15 20 25 30 35 40 45 50 55 60 65

16. In a machine for loading shells, the combination with a series of independent plungers, of reciprocating actuating mechanism therefor yieldingly engaging the same whereby the plungers are operated in consonance with their actuating mechanism except when said plungers encounter a predetermined resistance, of a cross-head adapted to be interposed in the path of the plungers and move them forwardly with respect to their actuating mechanism, a locking pin normally holding said cross-head in inoperative position, means to disengage the locking pin from the cross-head, and a tension device adapted to move said cross-head into operative position when said locking pin is so disengaged. 100

17. In a machine for loading shells, the combination with a series of independent plungers, of reciprocating actuating mechanism therefor yieldingly engaging the same whereby the plungers are operated in consonance with their actuating mechanism except when said plungers encounter a predetermined resistance, of a cross-head adapted to be interposed in the path of the plungers and move them forwardly with respect to their actuating mechanism, a locking pin normally holding said cross-head in inoperative position, means operated by said actuating mechanism to disengage the locking pin from the cross-head, and a tension device adapted to move said cross-head into operative position when said locking pin is so disengaged. 105

18. In a machine for loading shells, the combination with a series of independent plungers, of reciprocating actuating mechanism therefor yieldingly engaging the same whereby the plungers are operated in consonance with their actuating mechanism except when said plungers encounter a predetermined resistance, of a cross-head adapted to be interposed in the path of the plungers and move them forwardly with respect to their actuating mechanism, a locking pin normally holding said cross-head in inoperative position, means to disengage the locking pin from the cross-head, a tension device adapted to move said cross-head into

operative position when said locking pin is so disengaged, and means arranged to be operated by said actuating mechanism to return the cross-head into inoperative position. 70

19. In a machine for loading shells, the combination with a series of independent plungers, of reciprocating actuating mechanism therefor yieldingly engaging the same whereby the plungers are operated in consonance with their actuating mechanism except when said plungers encounter a predetermined resistance, of a cross-head adapted to be interposed in the path of the plungers and move them forwardly with respect to their actuating mechanism, a locking pin normally holding said cross-head in inoperative position, a tripping bar operated by said actuating mechanism, connections to the locking pin including an abutment adapted to be moved into the path of the tripping bar to enable the latter to operate said connections to disengage the pin from the cross-head. 75 80 85

20. In a machine for loading shells, the combination with a series of independent plungers, of reciprocating actuating mechanism therefor yieldingly engaging the same whereby the plungers are operated in consonance with their actuating mechanism except when said plungers encounter a predetermined resistance, of a cross-head adapted to be interposed in the path of the plungers and move them forwardly with respect to their actuating mechanism, a locking pin normally holding said cross-head in inoperative position, a tripping bar operated by said actuating mechanism, connections to the locking pin including an abutment adapted to be moved into the path of the tripping bar to enable the latter to operate said connections to disengage the pin from the cross-head, a tension device adapted to move the cross-head into operative position when said locking pin is so disengaged, and means arranged to be operated by the actuating mechanism to return the cross-head to its inoperative position. 90 95 100 105 110

21. In a machine for loading shells, the combination with a series of independent plungers, of reciprocating actuating mechanism therefor yieldingly engaging the same whereby the plungers are operated in consonance with their actuating mechanism except when said plungers encounter a predetermined resistance, of a cross-head, locking devices thereon, one for each plunger, adapted to operate when the plungers are retracted to a definite extent, a second cross-head adapted to be interposed in the path of the plungers and move them forwardly with respect to their actuating mechanism, a locking pin normally holding the first cross-head in operative position, a second locking pin normally holding the second cross-head in 115 120 125 130

inoperative position, means operated by said actuating mechanism to disengage both locking pins from their cross-heads, and tension devices adapted to move said cross-heads 5 from their normal positions when said locking pins are so disengaged.

21. In a machine for loading shells, the combination with the receptacle for the dynamite, and means for loading the dynamite 10 contained therein into the shells, of a traveling conveyer adapted to convey dynamite to the receptacle, a shaft driving said conveyer, a pulley on said shaft, the driving shaft, a clutch member and pulley loose on the driving shaft, a belt connecting said pulleys, a clutch member rotating with, but movable along, the driving shaft, a pressure cylinder, a plunger therein, a pivoted lever attached 15 to said movable clutch member and said plunger, a pressure supply pipe leading to 20 said cylinder, and a valve on said pipe.

22. In a machine for loading shells, the combination with the drum for holding the shells into which the dynamite is loaded, of 25 reciprocating plungers adapted to load the shells, a pressure cylinder, connections therefrom adapted to turn said drum, a valve controlling the admission of pressure fluid to said cylinder, and means to raise and lower the 30 drum into and out of operative relation with said plungers and operate said valve.

23. In a machine for loading shells, the combination with the drum for holding the shells into which the dynamite is loaded and 35 shell-loading mechanism, of a ratchet on the drum shaft, a pawl adapted to operate the ratchet, a pressure cylinder, a plunger therein adapted to operate said pawl, a valve controlling the admission of fluid pressure to 40 said cylinder, and means to raise and lower the drum into and out of operative relation with said shell-loading mechanism and operate said valve.

24. In a machine for loading shells, the 45 combination with the shell-holder and shell loading mechanism, of vertically movable bars supporting the shell-holder, pressure cylinders, plungers therein connected with said bars, and equalizing mechanism connecting the bars.

25. In a machine for loading shells, the combination with the shell-holder and shell loading mechanism, of vertically movable bars supporting the shell-holder, pressure 55 cylinders, plungers therein connected with said bars, racks on said bars, a cross-shaft, and gears on the cross-shaft engaging said racks.

26. In a machine for loading shells, the 60 combination with the shell-holding drum and shell loading mechanism, of means to raise and lower the drum into and out of operative relation with the shell-loading mechanism, means to turn the drum when lowered, a device turning with the drum, and a locking

dog interposed in the path of travel of said device and adapted to arrest said device and hold the drum from rotation, said dog being movable with the drum when the latter is raised.

27. In a machine for loading shells, the combination with the shell-holding drum and shell-loading mechanism, of means to turn the drum, locking means adapted, when in normal position, to permit the drum to turn a predetermined distance and then hold it from further rotation, said locking means tending to move into operative position, a lever adapted to hold the locking means out of its normal position, and devices moving 70 with the drum, in the latter's rotation, adapted to operate said lever to release the locking means and permit it to move into normal position.

28. In a machine for loading shells, the combination with the shell-holding drum and shell-loading mechanism, of means to raise and lower and turn the drum, of locking means adapted to permit the drum, when lowered, to turn a predetermined distance 85 and arrest its further turning movement, and to lock the drum from turning, when raised, a lever adapted to hold said locking means out of operative position, and devices, turning with the drum, adapted to disengage said 90 lever from said locking means.

29. In a machine for loading shells, the combination with the shell-holding drum and shell-loading mechanism, of means to turn the drum, locking means adapted to stop the 100 rotation of the drum and hold it from further rotation, means to lift the drum and thus move it into operative relation with the shell-loading mechanism to enable the shells to be loaded while the drum is held from rotation, 105 said locking means being movable with the drum in the latter's lifting movement, a device adapted to engage said locking means, when the drum is lowered after the loading operation is completed, and withdraw the 110 same from engagement with said drum, and means turning with the drum to disengage said device from the locking means.

30. In a machine for loading shells, the combination with the shell-holding drum 115 and shell loading mechanism, of means to turn the drum, a dogging bar, devices turning with the drum adapted to engage the dogging bar, means to raise the drum, and thus move the same into operative relation with the shell-loading mechanism, a device adapted to withdraw and hold the dogging bar out of engagement when said drum is lowered, and pins turning with the drum adapted, in the latter's rotation, to release the dogging bar.

31. In a machine for loading shells, the combination with the shell-holding drum and shell loading mechanism, of means to turn the drum, a vertically movable dog-

ging bar, devices turning with the drum adapted to engage the dogging bar whereby the drum is stopped from further rotation and held in the position to which it is turned, means to lift the drum and dogging bar to bring the drum into operative relation with the shell-loading mechanism, a lever adapted to disengage the dogging bar to permit the drum to turn, and devices turning with the drum to disengage said lever from the dogging bar and permit the latter to move into operative position.

32. In a machine for loading shells, the combination with the drum for holding the shells into which the dynamite is loaded, of means to turn the drum, a dogging bar, a lever to hold the dogging bar out of operation, lugs turning with the drum adapted to engage the dogging bar and pins turning with the drum adapted to move said lever to release the dogging bar, said lugs and pins arranged alternately about the axis of the wheel.

33. In a machine for loading shells, the combination with the shell-holding drum, of means to turn the drum, a double-jawed vertically movable dogging bar, one of its jaws having a cam face, lugs on the drum adapted to successively engage the cam face of the last-named jaw and thereby lift said dog a limited distance, the other lug of the jaw being adapted to arrest the movement of said lugs, thereby stopping the turning movement of said drum, means to lift the drum and dog, a pin on said dog, a bell-crank lever, one arm of which is in line of movement of said pin as the dog moves vertically with the drum, means to limit the movement in one direction of said bell-crank on its pivot, whereby the dog is arrested on the downward movement of the drum and the dog thereby disengaged from the drum, and pins carried by the drum, the other arm of said bell-crank lever being in line of travel of the pins, whereby said bell-crank lever is operated to release said dog and permit it to drop into locking engagement.

34. In a machine for loading shells, the combination with the bodily movable shell-holder, shell-loading mechanism and folders adapted to fold in the outer ends of the loaded shells, of mechanism to operate the folders, means to raise the shell-holder into operative relation with the shell-loading mechanism and folders, and means operated by the shell-holder raising means to control the operation of the folder actuating mechanism.

35. In a machine for loading shells, the combination with the shell-holding drum, of folders adapted to fold in the outer ends of the shells, vertically movable bars carrying the shell-holding drum, mechanism to operate the folders, and means operated by the

drum-raising means to control the operation of the folder actuating mechanism.

36. In a machine for loading shells, the combination with the shell-holding drum, of a pressure cylinder, a plunger operated thereby, a folding bar operated by the plunger, a second folding bar, annular folders on the second folding bar adapted to bend in the ends of the shells, folding plungers on the first folding bar adapted to extend within the annular folders and to complete the folding, cylinders secured to one of the folding bars, pistons working therein and secured to the other folding bar, and a pipe admitting fluid pressure to the last named cylinders.

37. In a machine for loading shells, the combination with the shell-holding drum, of folders adapted to fold in the outer ends of the shells, a pressure cylinder, a plunger operated thereby and operating said folders, a valve controlling the admission of pressure fluid to said cylinder, means to raise the drum into operative relation with the folders, and means arranged to be operated by the drum-raising means to operate said valve.

38. In a machine for loading shells, the combination with the shell-holding drum, of folders adapted to fold in the outer ends of the shells, a pressure cylinder, a plunger operated thereby and operating said folders, a valve controlling the admission of pressure fluid to said cylinder, an arm on said valve, a lever connected with said arm, means to raise the drum into operative relation with the folders, and a device arranged to be operated by the drum raising means to operate said lever.

39. In a machine for loading shells, the combination with the shell-holding drum, of folders adapted to fold in the ends of the shells, a pressure cylinder and plunger to advance the folders, a pressure cylinder and plunger to retract the folders, means to raise the drum into operative relation with the folders, devices adapted to admit fluid pressure to the first named cylinder, a tripping lever arranged to be operated by the drum-raising means to cause said devices to operate, and means operated in the advance of the folders to move said tripping lever out of operative position.

40. In a machine for loading shells, the combination with the shell-holding drum, of folders adapted to fold in the ends of the shells, a pressure cylinder and plunger to advance the folders, a pressure cylinder and plunger to retract the folders, means to raise the drum into operative relation with the folders, a fluid pressure supply pipe, a pipe leading to the first named cylinder, a valve adapted to connect said pipe with either said supply or the exhaust, and devices operated by the drum-raising means to cause said

- valve to move to open communication from the source of fluid pressure supply pipe to said pipe.
41. In a machine for loading shells, the combination with the shell-holding drum, of folders adapted to fold in the ends of the shells, a pressure cylinder and plunger to advance the folders, a pressure cylinder and plunger to retract the folders, means to raise the drum into operative relation with the folders, a fluid pressure supply pipe, a pipe leading to the first-named cylinder, a valve adapted to connect said pipe with either said supply or the exhaust, a tripping lever arranged to be operated by the drum-raising means, devices operated by the tripping lever to move said valve to open communication from the source of fluid pressure supply to said pipe, a disengaging lever operated in the advance of the folders to move said tripping lever out of operative position, and means to move said valve to open communication between said pipe and the exhaust. 70
42. In a machine for loading shells, the combination with the shell-holding drum, of folders adapted to fold in the ends of the shells, a pressure cylinder and plunger to advance the folders, a pressure cylinder and plunger to retract the folders, means to raise the drum into operative relation with the folders, a fluid pressure supply pipe, a pipe leading therefrom to the first-named cylinder, a valve adapted to connect said pipe with either said supply or the exhaust, a tripping lever arranged to be operated by the drum-raising means, devices operated by the tripping lever to move said valve to open communication from the source of fluid pressure supply to said pipe, a disengaging lever operated in the advance of the folders to move said tripping lever out of operative position, a third cylinder communicating with said pipe, and a plunger therein connected with said devices and adapted to restore them to their initial position, thereby moving the valve to open communication from the said pipe to the exhaust. 80
43. In a machine for loading shells, the combination with the holder for the shells, of folders adapted to close the outer ends of the shells, a cylinder and plunger to advance the folders, devices adapted to connect the cylinder with either the supply or exhaust, drum-elevating means, a tripping lever actuated by the drum-elevating means to operate said devices to cause them to admit pressure to the first cylinder and means operated in the advance of the folders to disengage the tripping lever from said devices. 90
44. In a machine for loading shells, the combination with a shell holder, of folders adapted to close the outer ends of the shells, a cylinder and plunger to advance the folders, devices adapted to control the admission of pressure fluid to said cylinder, means for holding said devices in position to admit fluid, and means operated in the advance of the folders to release said holding means to permit said devices to shut off the supply of pressure fluid to said cylinder. 75
45. In a machine for loading shells, the combination with a shell holder, of folders adapted to close the outer ends of the shells, a cylinder and plunger to advance the folders, a cylinder and plunger means to retract the folders, devices adapted to control the admission of pressure fluid to the cylinder, means for holding said devices in position to admit fluid, means operated in the advance of the folders to release said holding means to permit said devices to shut off the supply of fluid to the cylinder, a second cylinder communicating with the first cylinder, and a plunger operated by the second cylinder adapted to so operate said devices. 85
46. In a shell-loading machine, the combination with the shell-holder, the shell-loading devices and their actuating mechanism, and means to unlock said devices to permit them to be operated by their actuating mechanism, of a vertically movable trough into which the loaded shells are discharged, mechanism connected with and adapted to raise said trough, and a common control device connected respectively with said unlocking means and said trough raising mechanism whereby the trough is raised during the loading operation. 90
47. In a shell-loading machine, the combination with the shell-holder and shell-loading mechanism, of means to raise and lower the shell-holder into and out of operative relation with the shell-loading mechanism, a vertically movable trough into which the loaded shells are discharged, mechanism connected with and adapted to raise said trough, and a common control device connected respectively with said drum raising means and said trough-raising mechanism whereby the trough is raised while the drum is in operative relation with the shell-loading mechanism. 100
48. In a shell-loading machine, the combination with the shell-holder, the shell-loading devices and their actuating mechanism, and means to unlock said devices to permit them to be operated by their actuating mechanism, of a vertically movable trough into which the loaded shells are discharged, a cylinder and piston controlling the operation of said unlocking means, a second cylinder and piston and connections therefrom to the trough whereby the latter is raised, and a common control device for admitting and exhausting fluid pressure to said cylinders whereby the trough is raised during the loading operation. 115
49. In a shell loading machine, the combination with the shell holder and shell loading mechanism, of means to raise and lower the shell-holder into and out of operative relation with the shell-loading mechanism, a cyl- 120
- 10 15 20 25 30 35 40 45 50 55 60 65 70 75 80 85 90 95 100 105 110 115 120 125 130

inder and piston by which the shell-holder is raised, a vertically movable trough into which the loaded shells are discharged, a second cylinder and piston and connections therefrom to the trough whereby the latter is raised, and a common control device for admitting and exhausting fluid pressure to said cylinders whereby the trough is raised during the loading operation.

50. In a shell loading machine, the combination with the shell-holder and the shell loading mechanism, means to turn the shell-holder while the shell-loading mechanism is inactive, devices controlling the discharge of the loaded shells, a trough into which the loaded shells so discharged are received, a cylinder and plunger, means controlling the admission of fluid pressure to the plunger, and connections from the plunger to the trough adapted to lift the latter from its shell-receiving position when the plunger is actuated by fluid pressure admitted to the cylinder.

51. In a shell loading machine, the combination with a revolving shell holding drum, of a vertically movable trough into which the shells are discharged, a pivoted frame supporting the trough, a cross-bar, links connecting the cross-bar and pivoted frame, a plunger connected with the cross-bar, and a fluid pressure cylinder operating said plunger.

52. In a shell loading machine, the combination with a revolving drum, of shuttles thereon comprising two parts extending in the direction of the drum axis and containing complementary shell receptacles; one of said parts being hinged, a cam lever to close the hinged part, a relatively fixed cam adapted in the rotation of the drum to move said cam lever into inoperative position, a lug on the hinged part, and a second fixed cam adapted in the rotation of the drum to engage said lug and open the hinged part.

53. In a machine for loading shells, the combination with the receptacle for the dynamite, of a shell-holder below the receptacle, plungers adapted to work through the receptacle and load the dynamite contained therein into the shells, of rotatable cross-shafts in the receptacle, respectively in front of and behind the plungers and fingers thereon clearing the front and rear faces of the plungers and working between them.

54. In a machine for loading shells, the combination with the receptacle for the dynamite, of a shell-holder below the receptacle, plungers adapted to work through the receptacle and load the dynamite contained therein into the shells, of rotatable cross-shafts in the receptacle, respectively in front of and behind the plungers and fingers thereon clearing the front and rear faces of the plungers, and having projections clearing the side faces of the plungers.

55. In a machine for loading shells, the

combination with the receptacle for the dynamite, of a shell-holder below the receptacle, plungers adapted to work through the receptacle and load the dynamite contained therein into the shells, of rotatable cross-shafts in the receptacle, respectively in front of and behind the plungers and fingers thereon clearing the front and rear faces of the plungers, alternate fingers on each shaft being arranged on opposite sides thereof.

56. In a machine for loading shells, the combination with the receptacle for the dynamite, of a shell-holder below the receptacle, plungers adapted to work through the receptacle and load the dynamite contained therein into the shells, of rotatable cross-shafts in the receptacle, respectively in front of and behind the plungers and fingers thereon clearing the front and rear faces of the plungers and working between them, and having projections clearing the side faces of the plungers.

57. In a machine for loading shells, the combination with a series of independent orificed plungers, of means for reciprocating them together, a cross-head, spring seated pins therein, one for each plunger, adapted to engage their respective plungers when the latter are raised to bring their orifices in line with said pins, and means to move the cross-head laterally, thereby disengaging said pins from their plungers.

58. In a machine for loading shells, the combination with a series of independent plungers, actuating mechanism therefor including means enabling each plunger to move relatively to said actuating mechanism when encountering a predetermined resistance, a locking device for each plunger to hold it out of action when the shell has been filled, mechanism to disengage the locking devices from the plungers, a pressure cylinder and plunger controlling the operation of said mechanism, a shell-holding drum adapted to be raised into operative relation with the plungers, a cylinder and plunger for raising the drum, a source of pressure supply, pipe connections to each cylinder, and a valve adapted to be operated to admit pressure to both cylinders.

59. In a machine for loading shells, the combination with a series of independent plungers, actuating mechanism therefor including means enabling each plunger to move relatively to said actuating mechanism when encountering a predetermined resistance, a locking device for each plunger to hold it out of action when the shell has been filled, means to depress the plungers when unlocked, to a common level, mechanism to disengage said locking devices and render said leveling means operative, a pressure cylinder and plunger controlling the operation of said mechanism, a shell-holding drum adapted to be raised into operative relation

with the plungers, a cylinder and plunger for raising the drum, a source of pressure supply, pipe connections to each cylinder, and a valve adapted to be operated to admit pressure to both cylinders.

60. In a machine for loading shells, the combination with a series of independent plungers, actuating mechanism therefor including means enabling each plunger to move relatively to said actuating mechanism when encountering a predetermined resistance, a locking device for each plunger to hold it out of action when the shell has been filled, mechanism to disengage the locking devices from the plungers, a pressure cylinder and plunger controlling the operation of said mechanism, a shell-holding drum adapted to be raised into operative relation with the plungers, a cylinder and plunger for raising the drum, a delivery trough to receive the loaded shells, a cylinder and plunger to raise said delivery trough, pipe connections to each cylinder, a source of pressure supply, and a valve adapted to be operated to admit pressure to all the cylinders.

61. In a machine for loading shells, the combination with a series of independent plungers, actuating mechanism therefor including means enabling each plunger to move relatively to said actuating mechanism when encountering a predetermined resistance, a locking device for each plunger to hold it out of action when the shell has been filled, means to depress the plungers when unlocked, to a common level, mechanism to disengage said locking devices and render said leveling means operative, a pressure cylinder and plunger controlling the operation of said mechanism, a shell-holding drum adapted to be raised into operative relation with the plungers, a cylinder and plunger for raising the drum, a delivery trough to receive the loaded shells, a cylinder and plunger to raise said delivery trough, pipe connections to each cylinder, a source of pressure supply, and a valve adapted to be operated to admit pressure to all the cylinders.

62. In a machine for loading shells, the combination with a series of independent plungers, actuating mechanism therefor including means enabling each plunger to move relatively to said actuating mechanism when encountering a predetermined resistance, a locking device for each plunger to hold it out of action when the shell has been filled, mechanism to disengage the locking devices from the plungers, a pressure cylinder and plunger controlling the operation of said mechanism, a shell-holding drum adapted to be raised into operative relation with the plungers, a cylinder and plunger for raising the drum, pipe connections to each cylinder, a

source of pressure supply, a valve adapted to be operated to admit pressure to all the cylinders, a folder to fold the ends of the loaded shells, a cylinder and plunger to operate the folder, and mechanism arranged to be operated by the drum when raised to cause the pressure fluid to actuate the last named plunger.

63. In a machine for loading shells, the combination with a series of independent plungers, actuating mechanism therefor including means enabling each plunger to move relatively to said actuating mechanism when encountering a predetermined resistance, a locking device for each plunger to hold it out of action when the shell has been filled, mechanism to disengage the locking devices from the plungers, a pressure cylinder and plunger controlling the operation of said mechanism, a shell-holding drum adapted to be raised into operative relation with the plungers, a cylinder and plunger for raising the drum, pipe connections to each cylinder, a source of pressure supply, a valve adapted to be operated to admit pressure to all the cylinders, a folder to fold the ends of the loaded shells, a cylinder and plunger to operate the folder, and mechanism arranged to be operated by the drum when raised to cause the pressure fluid to actuate the last named plunger, a cylinder and plunger to render the folder inoperative, and a valve arranged to be operated by the folder to shut off pressure fluid to the cylinder controlling the operation of the folder.

64. In a machine for loading shells, the combination with a series of independent plungers, actuating mechanism therefor including means enabling each plunger to move relatively to said actuating mechanism when encountering a predetermined resistance, a locking device for each plunger to hold it out of action when the shell has been filled, means to depress the plungers when unlocked, to a common level, mechanism to disengage said locking devices and render said leveling means operative, a shell-holding drum, mechanism to raise the drum into operative relation with the plungers, a folder to fold in the ends of the loaded shells, fluid pressure devices controlling the operation of said mechanism, drum and folder, and a common valve by means of which the operation of said fluid pressure devices is primarily controlled.

In testimony of which invention, I have hereunto set my hand, at Paulsboro, N. J., on this 26th day of November, 1906.

WILLIAM I. DONALDSON.
